UNITED STATES PATENT OFFICE.

PETER B. SHOEMAKER, OF PLATTSBURG, MISSOURI.

IMPROVED WASHING-MACHINE.

Specification forming part of Letters Patent No. 105,500, dated July 19, 1870.

To all whom it may concern:

Be it known that I, PETER B. SHOEMAKER, of Plattsburg, in the county of Clinton and State of Missouri, have invented a new and useful Improvement in Washing-Machines; and I do hereby declare that the following is a full, clear, and exact description thereof, which will enable others skilled in the art to make and use the same, reference being had to the accompanying drawings, forming part of this specification, in which.

Figure 1 is a detail vertical section of my improved machine, taken through the line x , Fig. 2. Fig. 2 is a detail vertical section of the same, taken through the line yy , Fig. 1.

Similar letters of reference indicate corresponding parts.

My invention has for its object to furnish an improved washing-machine, simple in construction, effective in operation, and easily operated, and which shall be so constructed as to wash the clothes by alternate pressure and saturation without rubbing, and consequently without injuring even the most delicate fabrics; and it consists in the construction and combination of the various parts of the machine, as hereinafter more fully described.

A is the body or tub of the machine, which is made semi-cylindrical in form, and which is supported upon legs B, of such a length as to raise the machine to a convenient height. In the sides of the tub A are secured inclined racks C, formed by attaching cross-bars with their forward edges rounded off to side bars, as shown in Figs. 1 and 2.

D is the middle part of the top or cover of the machine, which is stationary, and is permanently attached to the upper edges of the said tub.

E are the side parts of the cover, which are hinged at their inner edges to the edges of the central stationary part, D, so that they may be turned up for convenience in putting in and taking out the clothes.

To the stationary part D of the cover is attached a support or bracket, F, in the central part of which is formed a socket to receive the standard G, which is secured at any desired

elevation by a set-screw passing in through the side of the said socket and pressing against the said standard.

To the upper end of the standard G is pivoted the center of the equal-armed lever H, by which the machine is operated, and which is made of such a length that its hand-pieces h may project at the sides of the tub A.

To the lower side of the lever H are adjustably pivoted the upper ends of arms or bars I, so that the said bars or arms may be adjusted to work nearer to or farther from the vertical line, as may be desired. The bars or arms I pass down into the tub A through slots in the ends of the stationary part D of the cover, and to their lower ends are attached the pressers J, which are made of such a length as to extend across the tub A, and the end parts of which are slotted to allow the water pressed out of the clothes to escape through said slots. By this construction, as the lever H is operated the pressers J are forced down alternately upon the clothes upon the opposite sides of the tub A, the water is pressed out of them, and at the same time the clothes are turned or have their position changed, so as to be operated upon each time in a different part. As the pressers J move down the water forced before them rises or plows up through the spaces between the racks C and the curved sides of the tub A, the surging back of which water, upon the withdrawal of the pressers, materially assists in turning the clothes.

Having thus described my invention, I claim as new and desire to secure by Letters Patent—

An improved washing-machine formed by the combination of the stationary racks C, stationary part D of the cover, support or bracket F, adjustable standard G, lever H h', adjustable pivoted arms I, and pressers J with each other and with the semi-cylindrical tub A, said parts being constructed and operating substantially as herein shown and described, and for the purpose set forth.

PETER B. SHOEMAKER.
